UNITED STATES PATENT OFFICE.

JAMES MAXWELL BULLOCK, OF PHILADELPHIA, PENNSYLVANIA.

DESIGN FOR A SAMPLE-PACKAGE.

43,795.

Specification for Design.

Patented Apr. 1, 1913.

Application filed July 16, 1912. Serial No. 709,823. Term of patent 14 years.

To all whom it may concern:

Be it known that I, JAMES MAXWELL BULLOCK, a citizen of the United States, residing at Philadelphia, in the county of Philadelphia and State of Pennsylvania, have invented a new, original, and ornamental Design for Sample-Packages, of which the following is a specification.

Reference is had to the accompanying drawing, in which the figure is an elevation of a sample mailing package, showing my new and ornamental design.

As shown in the drawing, the leading or material feature of my design consists of an ornamental panel 1 extending across a rectangular body 2, which has a marginal border 3. Within the transverse panel are arranged parallel rows of circular depressions 4 and 5, connected in pairs by border lines 6 having circular end portions concentric with the circular depressions. The cir-

cular depressions 5 of one of the transverse series of rows are surrounded by circular slits 7, having straight terminal extensions 8 located at the spaces between the two rows of depressions and arranged in parallelism with the border lines 6. The border lines 6 are provided at opposite sides with central ornamental scrolls 9 and ornamental figures 10 are located between the border lines at the terminal portions thereof.

I claim:—

The ornamental design for a sample package, as shown and described.

In testimony that I claim the foregoing as my own, I have hereto affixed my signature in the presence of two witnesses.

JAMES MAXWELL BULLOCK.

Witnesses:

PHILIP J. GANNON,
JOHN L. MOUNCE.
